UNITED STATES PATENT OFFICE.

FRANK MAUS, OF SAN JOSE, CALIFORNIA, ASSIGNOR OF ONE-HALF TO SIEBREN J. SPOELSTRA, OF SAN JOSE, CALIFORNIA.

DEHYDRATOR.

1,402,306.

Specification of Letters Patent. Patented Jan. 3, 1922.

Application filed February 10, 1921. Serial No. 444,006.

To all whom it may concern:

Be it known that I, FRANK MAUS, a citizen of the United States, and resident of San Jose, in the county of Santa Clara and State of California, have invented certain new and useful Improvements in Dehydrators, of which the following is a specification.

It is the object of this invention to provide a dehydrator for nuts, prunes and other material which may be adapted to use any one of several different processes of dehydration, or certain combinations of said processes, reference being made to my co-pending applications as follows:—

Method of dehydration and apparatus therefor, Serial No. 438,713, filed Jan. 20, 1921.

Method of cooling and dehydrating materials, Serial No. 441,608, filed Feb. 1, 1921.

Method of and apparatus for dehydrating materials, Serial No. 441,609, filed Feb. 1, 1921.

Method of and apparatus for dehydrating materials, Serial No. 441,610, filed Feb. 1, 1921.

Method of and apparatus for dehydrating materials, Serial No. 442,261, filed Feb. 3, 1921.

30 In the drawings:

Figure 1 is a vertical and longitudinal section through a dehydrator embodying my invention, parts being broken away.

Figures 2 to 9 inclusive are diagrammatic illustrations showing the several adaptations of the same.

Referring more particularly to the drawing, 1 indicates a dehydration chamber or tunnel provided with doors 2—2 and a track 3 over which are moved trucks 4 carrying trays 5 upon which are arranged the materials to be treated. Arranged over chamber 1 is a conduit 6 having heating elements 7 arranged therein supplied with steam or other suitable heating medium through a pipe as 8. A chamber is shown at 9 communicating with conduit 6 through valve 10 and with the atmosphere through valve 11, the said chamber also communicating 50 with chamber 1 through passage 12 and fan 13, the fan 13 being operated in any suitable manner through the medium of pulley 14. Arranged over chamber 1 and conduit 6 and adjacent to chamber 9 is shown a refriger-

erating chamber 15 fitted with baffle plates 16 to form compartments 16^a—16^b—16^c—16^d—16^e, in the latter four of which are arranged suitable refrigerating coils as 17. Refrigerating chamber 15 is provided with a drain at 16^f and air valves at 18 and 19 respectively, the former communicating with the atmosphere at the base of compartment 16^a and the latter communicating with the atmosphere at the upper end of compartment 16^e.

At 20 is shown a conduit arranged at a slight incline and extending from refrigerating chamber 15 to the opposite end of chamber 1 with which it communicates through passage 21, a fan 23 being located 65 thereon as shown. An air passage is shown at 22 communicating with conduit 20 adjacent to fan 23 and with conduit 6 through valve 24. A plurality of pipes 25 are shown communicating with the lower portion of 70 compartment 16^a in chamber 15 and extending through conduit 20 to a point adjacent to passage 22 where they terminate in a plate 26 forming the upper end of passage 27 positioned adjacent to passage 22 and communicating with conduit 6. The flow of air 75 through passage 27 is controlled by valve 24 which is pivoted at 28 and operated in any suitable manner as by a rod 29. Conduit 20 discharges into the atmosphere 80 through valve 30 and pipe 31, or into compartment 16^e of chamber 15 through valve 32.

At the end of conduit 20 adjacent to fan 23 is provided an air valve 33 through 90 which air is discharged into pipe 34 and thence to the atmosphere. A second air valve is arranged at 35 communicating with the atmosphere and chamber 20, a stop being placed in the bottom of conduit 20 as at 36 95 so that either valve 33 or 35 may be used to close off conduit 20 at this point.

At a suitable point in conduit 20 and intermediate discharge pipes 31 and 34, are arranged air valves 37 and 38, the former 100 communicating directly with the atmosphere and the latter communicating with the atmosphere through discharge pipe 39. Conduit 20 has a division wall mounted therein as at 40 extending above pipes 25 and forming opening 41 which may be closed by valve 38.

Assuming the fans to be in operation and

the several valves to be arranged as shown, the air is circulated through chamber 15, pipes 25, passage 27, conduit 6, chamber 9, fan 13, chamber 1, passage 21, fan 23, conduit 20 and through open valve 32 back into chamber 15 thereby forming a closed circuit dehydrator. In this arrangement the material treated is passed through chamber 1 in a direction opposite to the direction of the air flow therethrough the heated and moist air being exhausted into conduit 20 where its temperature is progressively lowered and its moisture content reduced as heat is absorbed therefrom by the cold dry air passing through pipes 25. When this exhaust dehydration air passes through chamber 15 the remaining moisture is extracted and it is passed into pipes 25 where its temperature is again raised to a point approaching that of the exhaust dehydration air at its point of discharge into conduit 20. When this temperature is not sufficiently high the heating elements in conduit 6 are used to provide the required additional heat. In the embodiment shown in Figure 2 valves 19 and 30 are open and valve 32 is closed so that air is drawn from the atmosphere through valve 19 into chamber 15, then passed through the dehydrator as above described and discharged therefrom through the open valve 30 into pipe 31 and thence to the atmosphere. In this arrangement the air is drawn directly from the atmosphere, cooled and dried in chamber 15, and then passed through conduits 25 where it picks up heat from the exhaust air from the dehydration chamber 1, the latter surrendering a large portion of its heat to the said air in pipes 25 and finally discharging into the atmosphere. In the embodiment shown in Figure 3, valve 35 is open and valve 33 opened and the other valves arranged so that the air entering through valve 35 passes through the conduit 20 around pipes 25, thence through valve 32, chamber 15, pipes 25, passage 27, conduit 6, chamber 9, fan 13, chamber 1, passage 21, fan 23 and valve 33 to pipe 34 and thence to the atmosphere. In this arrangement of valves the air drawn from the atmosphere is utilized to raise the temperature of the cold dry air in pipes 25 to a point approaching atmospheric temperature. Any additional heat required is provided by heating elements 7. In this as in all the other embodiments of the invention, the material being treated moves through chamber 1 in a direction opposite to the direction of the air flow therethrough. In the embodiment shown in Figure 4, valve 41 is closed and valves 38 and 37 are opened and the other valves are arranged so that the air is drawn from the atmosphere through valve 37 into conduit 20 and passed around pipes 25, thence through valve 32,

chamber 15, pipes 25, passage 27, conduit 6, chamber 9, fan 13, chamber 1, passage 21, fan 23 and again through a portion of conduit 20 and around pipes 25, thence through valve 38 and pipe 39 to the atmosphere. In this arrangement the air at atmospheric temperature is utilized to partially raise the temperature of the air in pipes 25 and the same air after being exhausted from the chamber 1 is again utilized to still further raise the temperature of the air in pipes 25 before again being discharged into the atmosphere.

In the embodiment shown in Figure 5 valve 18 is opened and thrown into the position 18^a where it closes off compartment 16^a and permits air to be drawn directly from the atmosphere into pipes 25, the refrigerating chamber not being used. The other valves are now arranged so that the air now moves through pipes 25, passage 27, conduit 6, chamber 9, fan 13, passage 12, chamber 1, passage 21, fan 23 and conduit 20 around pipes 25 to valve 30, through which it passes into pipe 31 and thence to the atmosphere. In this arrangement the dehydration air is drawn directly from the atmosphere into pipes 25 and therein heated to a temperature approaching that of the exhaust dehydration air at its point of discharge into conduit 20, and by heat extracted from said exhaust dehydration air, before it is passed through conduit 6 to chamber 1. The heating elements 7 are used, of course, if additional heat is required to raise the temperature of the air discharged from pipes 25 to a suitable point.

In the embodiment shown in Figure 6 valve 11 is open and valve 10 closed and the other valves arranged so that air is drawn from the atmosphere into chamber 9, then passed through fan 13, passage 12, chamber 1, passage 21, fan 23, conduit 20, valve 33 and pipe 34 to the atmosphere. In this arrangement dry atmospheric air is passed directly through the dehydration chamber and discharged therefrom without the precooling and heating hereinbefore described.

In the embodiment shown in Figure 7, the valve 18 is opened to the position 18^a to close off the refrigerating chamber 15, and the other valves are arranged so that the air is passed through pipes 25, passage 27, conduit 6, chamber 9, fan 13, chamber 1, passage 21, fan 23, conduit 20, valve 33 and pipe 34 to the atmosphere. In this arrangement the air is drawn directly from the atmosphere and passed into conduit 6 and chamber 1 without precooling and is heated only through the use of the heating elements 7. The same result is obtained if the air is admitted to conduit 6 through a valve as 42 communicating directly therewith.

In the embodiment shown in Figure 8 a portion of valve 18 is opened to 18^a thereby

closing off the refrigeration chamber, and a second portion 18^b is opened a distance as shown thereby limiting the air inflow, and valve 24 is swung to the position shown to 5 partly close off passage 22, the valve 30 being partly open and the other valves being arranged so that the air flows through pipes 25 to passage 27, thence through conduit 6, chamber 9, fan 13, chamber 1, passage 21, 10 fan 23, and into conduit 20. Since the air inflow is throttled down by valve 18^b, and since valve 24 is partly opened a portion of the air flowing into conduit 20 is drawn through valve 24 into conduit 6 and recirculated through the dehydrator, the balance passing on to valve 30, pipe 31 and thence to the atmosphere. This arrangement is utilized, for instance, when the dehydration air discharged into conduit 20 does not 15 carry sufficient moisture to warrant its entire discharge from the dehydrator, heat energy being conserved by recirculating a portion of the said dehydration air through the dehydrator chamber.

25 In Figure 9 the valves are arranged in a manner similar to that described in connection with Figure 8 except that the valves are arranged so that the air is discharged from the dehydrator chamber through the 30 partly opened valve 33 into pipe 34 and thence to the atmosphere, this exhaust air not being used for raising the temperature of the inflowing air.

It may now be seen that a dehydrator of 35 this type may be adapted for use under every atmospheric condition as to temperature and humidity, and for various methods of heat recovery, and also throughout a wide variation in the treatment of the material introduced into chamber 1. The treatment 40 of the material varies of course, according to the nature of the material and its condition and temperature when introduced into the chamber, and the result desired upon 45 its discharge therefrom.

It is to be understood, of course, that while I have herein shown and described the particular form of the invention deemed most practical, changes in form, construction and method of operation may be made within the scope of the appended claims.

I claim:

1. A dehydrator including a dehydration chamber, a refrigeration chamber, a conduit connecting the air discharge end of the dehydration chamber with one end of the refrigeration chamber, a valve controlled port between said conduit and chamber, a conduit connecting the air receiving end of the dehydration chamber with the other end of the refrigeration chamber, one conduit having a portion of its length enclosed by the other conduit, means for creating a circulation of air through said conduits and chambers, a valve controlled air inlet port to the

refrigeration chamber, and a valve controlled air discharge port from the first mentioned conduit at the end thereof adjacent said refrigeration chamber.

2. A dehydrator including a dehydration chamber, a refrigeration chamber, a conduit connecting the air discharge end of the dehydration chamber with one end of the refrigeration chamber, a valve controlled port between said conduit and chamber, a conduit 70 connecting the air receiving end of the dehydration chamber with the other end of the refrigeration chamber, one conduit having a portion of its length enclosed by the other conduit, means for creating a circulation of 75 air through said conduits and chambers, a valve controlled air inlet port to the refrigeration chamber, a valve controlled air discharge port from the first mentioned conduit at the end thereof adjacent to said refrigeration chamber, and air inlet and discharge ports at the air receiving end thereof, 80 and means for closing said conduit at a point between said inlet and discharge ports last 85 mentioned.

3. A dehydrator including a dehydration chamber, a refrigeration chamber, a conduit connecting the air discharge end of the dehydration chamber with one end of the refrigeration chamber, a valve controlled port 95 between said conduit and chamber, a conduit connecting the air receiving end of the dehydration chamber with the other end of the refrigeration chamber, one conduit having a portion of its length enclosed by the other conduit, means for creating a circulation of 100 air through said conduits and chambers, a valve controlled air inlet port to the refrigeration chamber, a valve controlled air discharge port from the first mentioned 105 conduit at the end thereof adjacent to said refrigeration chamber, and air inlet and discharge ports arranged intermediate the length thereof, and means for closing said conduit at a point between said last men- 110 tioned inlet and discharge ports.

4. A dehydrator including a dehydration chamber, a refrigeration chamber, a conduit connecting the air discharge end of the dehydration chamber with one end of the refrigeration chamber, a valve controlled port between said conduit and chamber, a conduit connecting the air receiving end of the dehydration chamber with the other end of the refrigeration chamber, one conduit having a 115 portion of its length enclosed by the other conduit, means for creating a circulation of air through said conduits and chambers, a valve controlled air inlet port to the refrigeration chamber, a valve controlled air discharge port from the first mentioned 120 conduit at the end thereof adjacent to said refrigeration chamber, air inlet and discharge ports at the air receiving end thereof, means for closing said conduit 125 130

1
at a point between said inlet and discharge ports, and air inlet and discharge ports arranged intermediate the length of said conduit, and means for closing said conduit 5 at a point between said last mentioned inlet and discharge ports.

5. A dehydrator including a dehydration chamber, a refrigeration chamber, a conduit connecting the air discharge end of the dehydration chamber with one end of the refrigeration chamber, a conduit connecting the air receiving end of the dehydration chamber with the other end of the refrigeration chamber, one conduit having a portion 10 of its length enclosed by the other conduit, means for creating a circulation of air through said conduits and chambers, an air inlet port to the refrigeration chamber, an air discharge port from the first mentioned 15 conduit at the end thereof adjacent to the said refrigeration chamber, air inlet and discharge ports at the air receiving end thereof, means for closing said conduit at a point between said last mentioned 20 inlet and discharge ports, air inlet and discharge ports arranged intermediate the length of said conduit, and means for closing said conduit at a point between said last mentioned 25 inlet and discharge ports.

30 6. A dehydrator including a dehydration chamber, a refrigeration chamber, a conduit connecting the air discharge end of the dehydration chamber with one end of the refrigeration chamber, a conduit connecting the air receiving end of the dehydration chamber with the other end of the refrigeration chamber, one conduit having a portion 35 of its length enclosed by the other conduit, means for creating a circulation of air through said conduits and chambers, an air inlet port to the refrigeration chamber, an air discharge port from the first mentioned 40 conduit at the end thereof adjacent to said refrigeration chamber, air inlet and discharge 45 ports at the air receiving end of said conduit, and means for closing said conduit at a point between said inlet and discharge ports.

7. A dehydrator including a dehydration 50 chamber, a refrigeration chamber, a conduit connecting the air discharge end of the dehydration chamber with one end of the refrigeration chamber, a conduit connecting the air receiving end of the dehydration chamber with the other end of the refrigeration chamber, one conduit having a portion 55 of its length enclosed by the other conduit, means for creating a circulation of air through said conduits and chambers, an air inlet port to the refrigeration chamber, an air discharge port from the first mentioned 60 conduit at the end thereof adjacent to said refrigeration chamber, air inlet and discharge ports arranged intermediate the length of said conduit, and means 65

for closing said conduit at a point between said last mentioned inlet and discharge ports.

8. A dehydrator including a dehydration chamber, a refrigeration chamber, a conduit 70 extending from the air discharge end of the dehydration chamber to a point adjacent to said refrigeration chamber and discharging into the atmosphere, a conduit connecting the air receiving end of the dehydration 75 chamber with the air discharge end of the refrigeration chamber, one conduit having a portion of its length enclosed by the other conduit, means for creating a circulation of air through said conduits and chambers, an 80 inlet port to the refrigeration chamber, and a valve controlled air discharge port arranged in said first conduit at the air receiving end thereof, and means for closing said conduit at a point adjacent to the said 85 discharge port to direct exhaust air therethrough.

9. A dehydrator including a dehydration chamber, a refrigeration chamber, a conduit extending from the air discharge end of the 90 dehydration chamber to a point adjacent to said refrigeration chamber and discharging into the atmosphere, a conduit connecting the air receiving end of the dehydration chamber with the air discharge end of the 95 refrigeration chamber, one conduit having a portion of its length enclosed by the other conduit, means for creating a circulation of air through said conduits and chambers, an inlet port to the refrigeration chamber, and 100 a valve controlled air discharge port arranged in said first mentioned conduit at a point intermediate its length, and means for closing said conduit at a point adjacent to the said discharge port to direct exhaust air 105 therethrough.

10. A dehydrator including a dehydration chamber, a refrigeration chamber, a conduit extending from the air discharge end of the dehydration chamber to a point 110 adjacent to said refrigeration chamber and discharging into the atmosphere, a conduit connecting the air receiving end of the dehydration chamber with the air discharge end of the refrigeration chamber, one conduit having a portion of its length enclosed by the other conduit, means for creating a 115 circulation of air through said conduits and chambers, an inlet port to the refrigeration chamber, a valve controlled air discharge port arranged in said first mentioned conduit at the air receiving end thereof, a valve controlled air discharge port arranged in said conduit intermediate its length, and means for closing said conduit at points adjacent to said discharge ports to direct exhaust air 120 therethrough.

11. A dehydrator including a dehydration chamber, a refrigeration chamber, a conduit connecting the air discharge end of 125

- the dehydration chamber with one end of said refrigeration chamber, a conduit connecting the air receiving end of the dehydration chamber with the other end of the refrigeration chamber, one conduit having a portion of its length enclosed by the other conduit, means for creating a circulation of air through said conduits and chambers, an air inlet port to the refrigeration chamber, 5 means for introducing air into said second conduit at a predetermined point in its length, a valve controlled air discharge port in said first mentioned conduit at a point in the air receiving end thereof, and means for closing said conduit at a point adjacent to said last mentioned port to direct air there-through. 10
12. A dehydrator including a dehydration chamber, a refrigeration chamber, a conduit connecting the air discharge end of the dehydration chamber with the air receiving end of the refrigeration chamber, a conduit connecting the air receiving end of the dehydration chamber with the air discharge end of the refrigeration chamber, one conduit having a portion of its length enclosed by the other conduit, means for creating a circulation of air through said conduits and chambers, an air inlet port 15 to the refrigeration chamber, a second air inlet port to the refrigeration chamber at a point adjacent to the connection of the second mentioned conduit thereto, means for closing said refrigeration chamber and opening said last mentioned port whereby said second conduit is supplied with air direct from the atmosphere, an air discharge port from the first mentioned conduit at the end thereof adjacent to the air receiving end thereof, and means for closing said conduit at a point adjacent said last mentioned discharge port to exhaust air there-through. 20
13. The structure set forth in claim 11 provided with a valve controlled by-pass between the said conduits whereby a partial recirculation of the air is effected. 25
14. The structure set forth in claim 11 provided with a by-pass between the said conduits and a valve operatively arranged with relation to both the by-pass and one conduit. 30
15. The structure set forth in claim 1 provided with heating elements arranged in the second conduit. 35
16. A dehydrator including a dehydration chamber, an air supply conduit communicating therewith, an air exhaust conduit communicating therewith, one of said conduits passing through the other conduit, means for creating a circulation of air through said conduits and chamber, and a plurality of valve controlled air exhaust ports arranged at different points in said air exhaust conduit. 40
17. A dehydrator including a dehydration chamber, an air supply conduit communicating therewith, an air exhaust conduit communicating therewith, one of said conduits passing through the other conduit, 70 means for creating a circulation of air through the said conduits and chamber, and a plurality of valve controlled air inlet ports arranged at different points in said air supply conduit. 75
18. A dehydrator including a dehydration chamber, an air supply conduit communicating therewith, an air exhaust conduit communicating therewith, one of said conduits passing through the other conduit, 80 means for circulating air through said conduits and chamber, a plurality of valve controlled air exhaust ports arranged at different points in the length of said air exhaust conduit, and a plurality of valve controlled air inlet ports arranged at different points in the length of said air supply conduit. 85
19. A dehydrator including a dehydration chamber, an air supply conduit communicating therewith, an air exhaust conduit communicating therewith, one of said conduits passing through the other conduit, means for circulating air through said conduits and chamber, a plurality of valve controlled exhaust ports arranged in said exhaust conduit, a plurality of valve controlled air inlet ports arranged in said supply conduit, and means for cooling and drying the air before admitting the same to said air supply conduit. 90
20. A dehydrator including a dehydration chamber, an air supply conduit communicating therewith, an air exhaust conduit communicating therewith, one of said conduits passing through the other conduit, 105 means for circulating air through said conduits and chamber, a plurality of valve controlled air exhaust ports arranged at different points in said air exhaust conduit, and air heating means arranged in said air supply conduit. 110
21. A dehydrator including a dehydration chamber, an air supply conduit communicating therewith, an air exhaust conduit 115 communicating therewith, one of said conduits passing through the other conduit, means for creating a circulation of air through the said conduits and chamber, a plurality of valve controlled air inlet ports 120 arranged at different points in said air supply conduit, and air heating means arranged in said air supply conduit. 125
22. A dehydrator including a dehydration chamber, an air supply conduit communicating therewith, an air exhaust conduit communicating therewith, one of said conduits passing through the other conduit, means for circulating air through said conduits and chamber, a plurality of valve con- 130

trolled air exhaust ports arranged at different points in the length of said air exhaust conduit, and a plurality of valve controlled air inlet ports arranged at different points in the length of said air supply conduit, and air heating means arranged in said air supply conduit.

23. A dehydrator including a dehydration chamber, an air supply conduit communicating therewith, an air exhaust conduit 10 communicating therewith, one of said con-

duits passing through the other conduit, means for circulating air through said conduits and chamber, a plurality of valve controlled exhaust ports arranged in said exhaust conduit, a plurality of valve controlled air inlet ports arranged in said supply conduit, means for cooling and drying the air before admitting the same to said air supply conduit, and air heating means 15 arranged in said air supply conduit.

FRANK MAUS.
